UNITED STATES PATENT OFFICE.

JEAN A. LE ROY, OF NEW YORK, N. Y.

FILM-ADVANCING MEANS.

1,311,238.

Specification of Letters Patent. Patented July 29, 1919.

Application filed July 5, 1918. Serial No. 243,443.

To all whom it may concern:

Be it known that I, JEAN A. LE ROY, a citizen of the United States, and a resident of New York city, in the county of New York and State of New York, have invented certain new and useful Improvements in Film-Advancing Means, of which the following is a specification.

The invention relates to intermittent feed mechanism for apparatus employing a perforated strip of material, for example, such as the films employed in motion picture apparatus, including cameras, printers and projectors; and wherein a continuous rotation of a primary actuating member is converted into an intermittent feed of the said film before an aperture in the machine. Heretofore, various intermittently moving members, actuated from the continuously or intermittently rotating primary member, have been employed to attain this intermittent feeding of the film, such as the Geneva movement, embodying the star wheel and cam and pin-cross and cam, to intermittently rotate a sprocket or drum, the snail and pin movement, reciprocating grip devices or claw movements, beater movements embodying an eccentrically controlled cam and locking members. In addition, optical rectifiers have been used on a constantly feeding film; but all of the expedients enumerated involve mechanism of a more or less complicated nature, usually operating also with considerable noise, and more or less indirectly, whereas the herein disclosed mechanism is simple in construction and positive and satisfactory in its action.

The present invention contemplates the direct engagement of the film by a continuously rotating member, having film engaging means thereon, and so constructed that the said means are caused to enter and leave the perforations of the film in a positive, smooth, steady and rapid manner without any tendency to tear. The size, number and degree of separation of the film-engaging means may be so designed and selected as to accommodate the various sizes, styles of perforation of the film and velocities of feed of the latter. No back lash, furthermore, results from this improved feeding action, which is, moreover, accomplished in a noiseless manner and with a minimum of moving parts, being also reversible to run the film backwardly or to accommodate certain types

of films having laterally disposed series of exposures.

The nature of the invention will be best understood when described in connection with the accompanying drawings, in which—

Fig. 1 is a front elevation of the face plate or film supporting member of a motion picture apparatus, as one embodiment of the invention, said figure showing, also, the film gate or plate and the actuating handle for the mechanism.

Fig. 2 is a vertical section taken on the line 2—2, Fig. 1.

Fig. 3 is a rear view of one form of gate with tension shoe, which may be employed.

Fig. 4 is an end view thereof.

Fig. 5 is a side view, partly in section, illustrating a modified construction of shoe and gate.

Fig. 6 is a rear view, illustrating a further modification of shoe and gate.

Fig. 7 is a transverse section on an enlarged scale, taken on the line 7—7, Fig. 2, looking in the direction of the arrows.

Figs. 8 to 11 are fragmentary views illustrating the action of the film moving mechanism.

Fig. 12 is an end view of a modified form of the film-engaging element; and Fig. 13 is a front view illustrating a further modification of same.

Fig. 14 is a cross section showing a specific form of tooth which may be used.

Similar characters of reference designate corresponding parts throughout the several views.

Referring to the drawings, 20 designates the face plate of the head of a motion picture machine, the same being provided with a suitable aperture 21 and guide strips or tracks 22, running longitudinally thereof. Upon the tracks 22 is arranged to slide an apertured shoe plate or removable gate 23, the same being retained in position to register its aperture 24 with the aperture 21 by means of guide strips 25, and limited by a pin 26 engaging a shoulder 27 of the said apertured shoe plate. This plate is shown more particularly in Figs. 3 and 4 and consists of a thin strip of material, provided at one end with the aperture 24, and carrying along its sides shoe members 28 which extend around the ends of said shoe plate and over the inner face of the plate at each side, 105

being resiliently maintained in position relatively thereto by means of corresponding flat spring members 29. These spring members are secured substantially at the middle 5 of each plate, and run along the sides thereof, having their free ends passing through slots 30 over upturned ends of the shoe members 28. In this manner, the shoes are maintained under a constant and predetermined 10 tension; and when the apertured plate 23 is in position, as shown in Figs. 1 and 2 of the drawings, these shoes bear yieldingly against the film 32, holding the same to the face plate 20. Shoes 28, furthermore, are 15 provided with pairs of slots 33 and 34, symmetrically disposed with reference to the reversal of said plate 23, and are designed to permit the film-engaging means, hereinafter described, to pass therethrough.

20 The apertured plate and shoes may be variously arranged, for example, as shown in Fig. 5, the shoes 35 may be in one piece of resilient material which is brought around the ends of plate 36 and secured to the back 25 of same by means of a screw 37. Or, as shown in Fig. 6, the two shoes may move as a unit by providing connecting members 38 at the ends of same. From the foregoing, it will be appreciated that the film 32 may be 30 fed in the usual manner from a feed sprocket 40, providing a loop 41, to the face plate 20 and between same and the resilient shoes 28, as clearly shown in Fig. 2 of the drawings. It is to be understood, also, that the shoe 35 plate or removable gate is not restricted to the construction shown and described, but may consist of the usual hinged type correspondingly modified.

The invention herein has to do more particularly with the means for advancing the 40 film past the aperture 21 of the face plate 20 in manner to provide the necessary intermittent exposure of same before the said aperture. When it is desired to use the device as 45 a camera or printer, plate 23 may be reversed and present the opaque portion thereof before the aperture 21, thus preventing access of light to the interior of the inclosing cabinet through the last-named aperture. The 50 particular manner of effecting the intermittent movement of the film 32 past the aperture 21 is directly accomplished through the rotation of a cam film-engaging member 50, which is mounted to rotate with a shaft 51 55 whose rotation is effected through intermediate mechanism 52, manually through the operation of a crank or handle 53, or in any other convenient manner to obtain the desired speed.

60 The film-engaging means may consist of various forms of toothed members, for example, as indicated in Figs. 2 and 7 to 11, consisting of cam disks 54 with a plurality, for example three, sprocket teeth 55 designed to engage the 65 perforations 56 of film 32. Various modifica-

tions in the character of the film-engaging means may be employed, depending upon the particular style of film to be advanced, as for example, in Fig. 12, wherein is shown a cam disk 57 with but a single tooth 58. In 70 Fig. 13, the tooth 59 is of elongated character and is located in the middle of a cam drum 60, being designed to engage film having single perforations located between the pictures and midway of the film strip. Fig. 75 14 illustrates, in horizontal section, a particular form of tooth 61, having partly flattened instead of rounded face, the perforations for the film employed with this tooth being correspondingly formed. It is, therefore, to be understood that I do not limit myself to the particular character of tooth or number of teeth or number of series of teeth employed. The cam disks, in any event, are provided with a cam portion 62, 80 or with portions 62 and 63 where the arrangement is such that the film may be run in either direction, said cam portions being so arranged with reference to the teeth on the drum that engagement will be had with 85 the shoes 28 prior to the engagement of the teeth with the perforations of the film 32, and also prior to their disengagement therefrom. This action will be more clearly understood with reference to Figs. 8 to 11, 90 95 wherein the same is diagrammatically set forth. Fig. 8 represents the beginning of the action in which the cam portion 62, due to the interposition of the film 32, presses the shoes 28 away from the face plate and from 100 their normal position indicated in the dotted lines, so that when the first of the teeth 55 approaches the film 32 for engagement with a perforation, the film is slightly moved away from said tooth and gradually brought 105 thereover after the cam portion recedes, thus insuring a positive and smooth entry of the tooth into the perforation, Fig. 9, and without any tendency to tear the same. Similarly, as the last tooth is about to leave the 110 film, (Fig. 10 of the drawings), the cam 65 engages the shoe 28 through the interposition of film 32, forcing both film and shoe slightly away from the receding tooth without shock or tendency to tear. When film and teeth 115 are totally disengaged, the film is at rest and before the aperture 21 in position for exposure, printing or projecting, and continues in this position until cam 62 again moves out the film and shoe, and the forward tooth of 120 the series enters into engagement with the corresponding perforation of the film. During this entire period of rest, the surface of the cam disk 54 clears the film, Fig. 11. In the event of no film being in position, the 125 slots 34 permit the high portions and teeth of the disks to project through the shoes; and it is only when a film intervenes that the same are moved out of their normal positions to the positions indicated in Figs. 8 and 10. 130

It is to be understood, of course, that the action herein described is entirely reversible and suited to the operation of the film backwardly, or to accommodate certain types of 5 films having laterally disposed series of exposures.

It has been found convenient, moreover, in order to render the apparatus suitable for printing and photographic work, to surround the drum and film-advancing mechanism with a suitable cover or casing 65, which is attached back of the face plate in order to prevent access of light through slots 33 or 34 of the shoes 28, as well as to 10 serve as a protective cover for the film-advancing member. A cover 66 may, also, be fitted over the intermediate mechanism 52 to shut out any light entering through slot 67 through which this intermediate mechanism 15 passes.

I claim:

1. Advancing mechanism for perforated strips, comprising: a continuously rotating element carrying means to intermittently 25 engage the perforations of said strip; an apertured support in relation to which said strip is designed to move; resilient means to retain the strip against said support, said means being designed to permit the engaging 30 element to pass therethrough, and yieldable under contact with same through the interposition of the strip.

2. Advancing mechanism for perforated strips, comprising: a continuously rotating element embodying a cam portion associated 35 with engaging means to intermittently engage the perforation of said strip; an apertured support in relation to which said strip is designed to move; an apertured plate to 40 retain the strip against said support, said plate carrying means designed to permit the engaging element to pass therethrough, and yieldable under contact with same through the interposition of the strip.

45 3. Advancing mechanism for perforated strips, comprising: a continuously rotating element embodying a cam portion associated with engaging means to intermittently engage the perforation of said strip; an apertured support in relation to which said strip is designed to move; a removable apertured plate to retain the strip against said support, said plate carrying means designed to 50 permit the engaging element to pass therethrough, and yieldable under contact with same through the interposition of the strip.

4. Advancing mechanism for perforated strips, comprising: a continuously rotating element embodying a cam portion associated 60 with engaging means to intermittently engage the perforation of said strip; an apertured support in relation to which said strip is designed to move; an apertured plate to retain the strip against said support and including means provided with slots through 65

which the engaging element may pass, said means being yieldable under contact with the engaging element through the interposition of the strip.

5. Advancing mechanism for perforated strips, comprising: a continuously rotating element embodying a cam portion associated with engaging means to intermittently engage the perforation of said strip; an apertured support in relation to which said strip is designed to move; a removable apertured plate to retain the strip against said support and including means provided with oppositely disposed slots through which the engaging element may pass, said means being yieldable under contact with the engaging element through the interposition of the strip.

6. Advancing mechanism for perforated strips, comprising: a continuously rotating element embodying a cam portion associated with engaging means to intermittently engage the perforation of said strip; an apertured support in relation to which said strip is designed to move; a removable apertured plate to retain the strip against said support and including resilient means provided with oppositely disposed slots through which the engaging element may pass, said resilient means being yieldable under contact with the engaging element through the interposition of the strip.

7. Advancing mechanism for perforated strips, comprising: a continuously rotating element carrying means to intermittently engage the perforations of said strip; an apertured support in relation to which said strip is designed to move; a reversible and removable apertured plate to retain the strip against said support and including resilient means having two sets of oppositely disposed slots through which the engaging element may pass, said resilient means being yieldable under contact with the engaging element through the interposition of the strip.

8. Advancing mechanism for perforated strips, comprising: a rotatable element provided with means to engage the perforations of said strip; an apertured support in relation to which said strip is designed to move; a reversible and removable apertured plate to retain the strip against said support and including resilient means having two sets of oppositely disposed slots, the said plate being provided with an aperture positioned relatively to the one pair of slots, and with an opaque portion to obstruct the passage of light when the plate is reversed.

9. Advancing mechanism for perforated strips, comprising: a continuously rotating element embodying a cam portion associated with engaging means to intermittently engage the perforation of said strip; an apertured support in relation to which said strip

is designed to move; a plate to retain the strip against said support and including yielding shoe members resiliently carried by said plate and extending over the ends of same, 5 said shoe members being provided with slots through which the engaging element may pass.

10. Advancing mechanism for perforated strips, comprising: a rotatable element provided with means to engage the perforations of said strip; an apertured support in relation to which said strip is designed to move; a removable and reversible apertured plate to retain the strip against said support and 15 including yielding shoe members resiliently carried by said plate and extending over the ends of same, said shoe members being provided with oppositely disposed slots through which the engaging element may 20 pass.

11. Advancing mechanism for perforated strips, comprising: a rotatable element embodying a toothed and cam member, the toothed portion of which is adapted to engage the perforations of the said strip to advance the latter, and the cam portion to move the strip substantially at right angles to its direction of advance.

12. Advancing mechanism for perforated strips, comprising: a rotatable element embodying a toothed portion and cam portions between which said toothed portion is located, the toothed portion being adapted to engage the perforations of the said strip to 35 advance the latter, and the cam portions to move the strip substantially at right angles to its direction of advance.

13. Advancing mechanism for perforated strips, comprising: a rotatable element having two cam portions thereon and an intermediate toothed portion, the first cam portion being adapted to move the strip substantially at right angles to its direction of advance just prior to the engagement of the 40 toothed portion with the perforations of said strip, and the second cam portion being adapted to move said strip substantially at right angles to its direction of advance just prior to the disengagement of the 45 toothed portion from the perforations of said strip.

14. In a motion picture apparatus: a constantly rotatable feed sprocket for a perforated strip; a support provided with an

aperture in relation to which said strip is 55 designed to move; means to retain the strip against said support; and means to intermittently advance the strip past the aperture, and comprising a rotatable element embodying a toothed portion and cam portions 60 between which said toothed portion is located, the toothed portion being adapted to engage the perforations of said strip to advance the latter, and the cam portions to move the strip substantially at right angles to its direction of advance.

15. In a motion picture apparatus: means to continuously feed forward a perforated strip; an apertured plate, and means to position the strip with reference thereto and 70 provide a loop portion in the strip; and advancing means to first force the strip outwardly substantially at right angles to its direction of advance, then engage and draw the same past the aperture of said plate, 75 and finally again force said strip outwardly substantially at right angles to its direction of advance.

16. The method of intermittently advancing a perforated strip, which consists in 80 continuously feeding forward said strip, positioning the same with reference to a support thereby providing a loop portion, and advancing the same with reference to said support by first forcing the strip outwardly 85 substantially at right angles to its direction of advance, and then engaging and drawing the same past said support.

17. The method of intermittently advancing a perforated strip, which consists in continuously feeding forward said strip, positioning the same with reference to a support thereby providing a loop portion, and advancing the same with reference to said support by first forcing the strip outwardly 90 substantially at right angles to its direction of advance to assist in the insertion of the strip, engaging means in the perforations of the strip, then engaging and drawing the strip past said support and again forcing 95 the same outwardly to assist in the release of the strip engaging means from the perforations of the strip.

Signed at New York in the county of New York and State of New York this 2nd day of July, A. D. 1918.

JEAN A. LE ROY.
